UNITED STATES PATENT OFFICE

EZRA B. MERRIAM, OF SWARTHMORE, PENNSYLVANIA, ASSIGNOR TO GENERAL ELECTRIC COMPANY, A CORPORATION OF NEW YORK

ELECTRIC CIRCUIT BREAKER

Application filed August 26, 1931. Serial No. 559,511.

My invention relates to electric circuit breakers, more particularly to electric switches of the fluid break or oil type, and has for its object the provision of an improved fluid break switch which shall have increased interrupting capacity and which shall be simple, rugged and inexpensive in construction.

In accordance with my invention a switch tank containing an insulating liquid, as oil, is provided with one or more, preferably two, lateral pockets or chambers forming restricted vents adjacent and opposite coacting switch contacts immersed in the oil within the switch tank. Upon opening movement of the switch contacts the corresponding arc drawn opposite and substantially at the entrance of a lateral chamber is urged by magnetic and other forces towards the interior 20 of said chamber, the resulting pressure generated by the arc within the restricted area of the chamber causing a so-called explosion chamber effect to interrupt the arc.

My invention will be more fully set forth 25 in the following description referring to the accompanying drawing, and the features of novelty which characterize my invention will be pointed out with particularity in the claims annexed to and forming a part of this 30 specification.

Referring to the drawing, Fig. 1 is an elevational view, partly in section, of an electric circuit breaker embodying my invention and Fig. 2 is a cross-sectional plan view taken 35 along the line 2—2 of Fig. 1.

The circuit breaker shown in Fig. 1 comprises certain features of a fluid break or oil switch of the conventional type including a pair of stationary contacts 1 interconnected 40 in the closed circuit position illustrated by a conducting bridging member 2, the contact structure being disposed within a switch tank 3 and immersed in an arc extinguishing or insulating liquid 4, as oil, contained therein. 45 The switch contact structure may be of any suitable type and in the present instance the bridging member 2 is connected to and operated by the lift rod 5 extending through and guided by the switch tank cover 6 for vertical movement. The stationary contacts 1 are

supported at the lower ends of the insulating bushings 7 extending through and mounted on the cover 6 and are electrically connected to the lead-in conductor studs 8 extending through the bushings 7. The circuit breaker 55 so far described is of the conventional type except for the fact that the coacting contact surfaces are generally spaced a greater distance than shown from the side walls of the tanks, the opening and closing operations of 60 the switch being effected merely by lowering and raising the bridging member 2 by the rod 5.

In the operation of a so-called plain break alternating current oil switch wherein the 65 bridging member simply separates from the coacting stationary contacts within a body of oil, the interrupting action is more or less fortuitous in view of the fact that the gas bubble formed in the oil and which serves as 70 a conducting medium for the arc, is finally broken up and displaced by oil mainly by the turbulence caused by the arc, and not by positive means. In interrupting an alternating current circuit an oil switch interrupts 75 when the current is passing through the zero value of the cycle thereby indicating that sufficient dielectric is interposed between the contacts at the zero point of the cycle to prevent reestablishment of the current. During 80 circuit interruption the arc is generating pressure at a high rate when the current is at the maximum value of the cycle, the rate decreasing as the current approaches the zero value. However, when the current has 85 reached the zero value the pressure generated in a plain break switch during the previous part of the cycle is of little aid in positive interruption of the circuit since the energy is freely dissipated in all directions 90 within the oil body.

For the purpose of more effectively and positively interrupting the current within a comparatively brief arcing period and for utilizing the pressure generated during arcing, the tank 3 is provided with a pair of lateral pockets or restricted chambers 9 formed by the wing-like metal extensions 10 welded or otherwise suitably joined to the steel tank 95 3. In the embodiment illustrated the lateral 100

chambers 9 are restricted in cross sectional area as compared with the tank 3 and are filled with oil, the oil level being at or slightly above the tops of the chambers. The tank 3 is provided with an insulating lining 11, the chambers 9 having insulating linings 12 extending through slots in the lining 11 to form arc receiving extensions of the chambers within or at the entrance of which the 10 coacting contact surfaces of the stationary contacts 1 and the bridging member 2 are disposed. The insulating linings 11 and 12 may be of suitable insulating material in sheet form, as a compound including a phenolic condensation product.

Accordingly, when the bridging member 2 is lowered the arcs drawn substantially transversely of and at the openings of the restricted lateral chambers 9 are urged by magnetic forces of the current traversing the U-shaped loop through the switch further into the corresponding chambers. Immediately upon separation of the contacts the heat of the resulting arcs generates high pressure in the 20 region of the contacts forming the well known gas bubble which is highly conducting and sustains the arc. In the present instance the arc is bowed or looped into the adjacent restricted chamber so that the pressure formed thereby tends to force oil mainly in one direction, that is from the chamber into the main oil body, as in the well known explosion chamber. During the higher values of the current the gas bubble maintains itself within 30 the lateral chamber due to the fact that additional gas is constantly being generated at a high rate by the heat of the arc. When the current reaches the zero part of the cycle, however, the rate of gas generation has accordingly decreased, thereby affording the best opportunity to interrupt the circuit. Since the pressure generated within the restricted chamber represents a certain amount of stored energy which is effective to force oil and gases at high velocity out of the pocket to cut off the arc the circuit is interrupted due to explosion chamber effect at the zero 40 part of the cycle. A circuit breaker so constructed in accordance with my invention not only increases by several times the interrupting capacity of a conventional plain break switch of similar size but interrupts short circuit currents quite consistently within a very brief interval of arcing.

In the preferred arrangement illustrated in Fig. 1, the switch tank is provided with a pair of lateral pockets, one for each break, it of course being understood that where necessary the size of the switch tank may be reduced by providing a single pocket at but one of the breaks. It is furthermore apparent that the oil within the switch tank need not completely fill the lateral pocket. In other words, the upper part of the pocket may be 50 designed to form an air cushion, instead of

utilizing the space above the oil level in the main tank, the lateral extension in this instance being provided likewise with an oil and gas baffle, as of the well known pebble type for freely venting gases and preventing 70 appreciable discharge of oil from the switch.

It should be understood that my invention is not limited to specific details of construction and arrangement thereof herein illustrated, and that changes and modifications 75 may occur to one skilled in the art without departing from the spirit of my invention.

What I claim as new and desire to secure by Letters Patent of the United States, is:

1. An electric circuit breaker comprising 80 relatively movable coacting contacts, and a tank containing insulating liquid in which said contacts are immersed, said tank provided with an extension forming a narrow lateral pocket opposite and adjacent said coacting contacts, said pocket being restricted in cross sectional area as compared with said tank and arranged so that the arc formed upon separation of said contacts is drawn transversely of the opening of said pocket. 90

2. An electric circuit breaker comprising a tank containing insulating liquid, and a pair of stationary contacts connected in the closed circuit position by a bridging member immersed in said liquid, said tank provided with wing-like extensions forming pockets restricted in cross-sectional area as compared with said tank, the opening of each pocket being opposite and adjacent a fixed contact 95 and said bridging member so that the arc drawn upon opening movement of said bridging member is substantially transversely of and at the entrance of said pocket. 100

3. A circuit interrupter comprising a tank 105 containing oil, relatively movable coacting contacts including a bridging member immersed in said oil, said tank provided with lateral wing-like extensions forming narrow restricted pockets at opposite sides of said tank, each of said pockets filled with oil and opening into said tank substantially at the point of separation of a pair of coacting contacts, and an insulating lining for each of said pockets forming the opening of the pocket in which the corresponding arc is drawn. 110

4. In an electric circuit breaker including coacting contacts separable within an arc extinguishing liquid, a switch casing containing said liquid provided with a lateral extension forming a pocket, said pocket being restricted in cross sectional area as compared with said casing, said coacting contacts positioned substantially at the entrance of said pocket so that an arc formed upon separation of the same is drawn transversely of the opening of said pocket. 120

In witness whereof, I have hereunto set my hand.

EZRA B. MERRIAM.
